Jonathan Dillon

United States Patent Office.

JONATHAN DILLON, OF NEW YORK, N. Y.

Letters Patent No. 93,070, dated July 27, 1869.

IMPROVEMENT IN CENTRE-BOARDS FOR VESSELS.

The Schedule referred to in these Letters Patent and making part of the same.

To all whom it may concern:

Be it known that I, JONATHAN DILLON, of the city, county, and State of New York, have invented a new and useful Improvement in "Adjustable Centre-Boards for Sailing-Vessels;" and I do hereby declare that the following is a full, clear, and exact description of the same, reference being had to the accompanying drawings, which form part of this specification.

This invention consists in a centre-board, composed of one or more folding leaves, similarly hinged to each other, and retained in a state of rigidity with respect to each other and to the hull, by a removable locking-rod passing through a socket in the hull, and through sockets formed in said leaves, whereby, upon the partial or entire withdrawal of the said rod, any or all the said leaves may, by means of a guy, be drawn up out of the way, to either side of the hull.

Referring to the accompanying drawings—

Figure 1 represents a longitudinal view of the hull of a vessel, provided with a centre-board, constructed according to my invention, and

Figure 2 represents an end view of the same, illustrating its operation in colored outlines.

Similar letters of reference indicate corresponding parts in both figures.

A is the hull of a vessel, B is a centre-board, having its upper edge hinged to the bottom of the hull, as shown, so as to admit of its being laterally folded to either side, so as, by the folding of the same, to allow of the passage of the vessel over shoals and other shallow places over which it would not otherwise pass. It is composed of one or more leaves, the lower, when more than one are used, being hinged to the upper, similar in manner to that in which the upper is hinged to the hull.

These folding leaves are each formed with a socket, c, for reception of a movable locking-rod, f.

Said rod f is also fitted in a socket, a, which passes in and through the bottom of the hull, and upward through the hull and cabin, so that while the said rod is fitted therein, and in the said sockets c, the centre-board is retained in a rigid pendent position.

By the partial withdrawal of the rod f, so that its lower end will clear the socket of the lower leaf or leaves, said lower leaf or leaves may, by means of a guy-rope, e, be drawn partially to the leeward side, thereby forming a cupped or concave surface, as illustrated in red outline, fig. 2, for the purpose of resisting more effectually the tendency of the vessel to drift in that direction.

By greater tension of the guy, as illustrated in blue outline, said portion of the centre-board may be drawn up out of the way, allowing thereby the passage of the vessel over shoals and shallow places, still leaving a portion of the centre-board to the action of the water.

By withdrawing the locking-rod f entirely above or out of the sockets e, of all the said leaves, the entire centre-board may be brought up flat against the bottom of the hull, as shown at x x, fig. 2.

The upper ends of the sockets c are or may be funnel-shaped, for facilitating the entrance of the locking-rod, and when desirable, an additional guy may be attached and used upon the opposite side of the vessel in connection with the guy e, to facilitate the adjustment of the centre-board preparatory to the lowering of the rod.

The guy or guys, when not in use, are carried aft, and are made fast to a suitable fastening, h, at or near the stern, where they may be in position to offer less resistance to forward motion, and where they may be less likely to gather or retain sea-weed or other matter.

What I claim as my invention, and desire to secure by Letters Patent, is—

The laterally-folding centre-board B, composed of one or more folding leaves, having sockets c, the removable locking-rod f, the fixed socket a, and the guy e, combined for operation, substantially as herein described.

JONATHAN DILLON.
